FILLING APPARATUS

Andrew J. Dowling and Edward Urbanski,
Philadelphia, Pa.

Application January 5, 1946, Serial No. 639,392

12 Claims. (Cl. 226—43)

(Granted under the act of March 3, 1883, as
amended April 30, 1928; 370 O. G. 757)

1

This invention relates to improvements in devices for filling containers in general and life preservers, life-saving equipment and other flotation gear with kapok in particular.

In the past, life preservers and other life-saving equipment was filled customarily with kapok by hand methods. This procedure caused a good deal of kapok and dust to be present in the room, creating a fire and explosion hazard. Hand methods also failed to fill the life-saving gear uniformly and compactly besides being slow, taking up a large amount of floor space and in general creating undesirable working conditions. The device herein disclosed is a mechanical apparatus for filling life-saving equipment that not only eliminates the disadvantages mentioned above but also eliminates the use of respirators for employees and reduces sewing costs because of the small insert openings required.

An object of this invention is to provide an apparatus for filling receptacles such as life-saving equipment with kapok or other material, which apparatus is simple to operate, involves an enclosed system for the material and is efficient in general.

Another object is to provide an apparatus for filling life-saving equipment that is pedal operated and eliminates the disadvantage of kapok being dispersed throughout the atmosphere of the room.

Further objects and advantages of this invention, as well as its construction, arrangement and operation, will be apparent from the following description and claims in connection with the accompanying drawings, in which

Fig. 1 is a top plan view of the filling apparatus, portions being shown in section for clarity of illustration;

Fig. 2 is a front view in elevation of the filling apparatus;

Fig. 3 is a side view in elevation of the filling apparatus, portions being shown in section;

Fig. 4 is a partial view in section showing the intake funnel;

Fig. 5 is a partial view showing a portion of the flap valve operating mechanism; and

Fig. 6 is a partial view showing the assembly of chain, rod, and sleeve.

Similar numerals refer to similar parts through the several views. A platform 10 is raised above the floor 11 of the room in which the apparatus is installed. Steps 12 provide easy access for the operator to mount the platform 10. Above the platform 10 is a table top or work

2

support 13 supported suitably from the platform 10 as by supports 14. Adjacent to the platform 10 and work support 13 is an entirely enclosed tank 15 for containing the fluffed kapok to be dispensed. A transparent plate 16 held by a frame 17 is provided to enable the operator to note the condition of the contents of the tank 15.

Mounted upon the work support 13 is a blower 20 having an intake pipe 21 leading into the tank 15. A funnel 22 is located within the tank 15 and is received slidably by the intake tube 21. Beneath the funnel 22 on a suitably mounted bracket 23 is a shelf 24 upon the inner end of which is located an upstanding bracket 25 for a purpose hereinafter disclosed.

Located at the mid horizontal plane of the funnel 22 is a hinge 30 (see Figs. 1 and 4) attached to the funnel 22, as by welding, the hinge 30 carrying rotatably an irregularly-shaped lever 31 between its ends. One end of the lever 31 has a disc 32, which in turn mounts a wooden disc 33, the wooden disc 33 acting as a valve or stopper for the funnel 22 and intake tube 21. The stopper 33 is held normally in closed position by means of a coil spring 34, which is fixed to the upper end of bracket 25 and the outer end of the lever 31.

The exhaust port 40 of the blower 20 has a square exhaust tube 41 attached thereto by means of the flanges 42. Fitted slidably into the exhaust tube 41 is a round filling tube 43. Integral with the exhaust tube 41 is a short projecting tube 44, also of square cross section. Attached to the projecting tube 44, as by the flanges 45, is a square return tube 46 which leads back into the tank 15. At the outer intersection of the square tube 41 and the square extending tube 44 is a spindle 47, which is held in place by means of a cotter pin 48. Integral with the spindle 47 and located outside the exhaust tube 41 is a crank or arm 49 having an eye 50 for a purpose hereinafter disclosed. Rolled around the spindle 47 and located within the exhaust tube 41 is a rectangular flap valve 51 adapted to close and open either the exhaust tube 41 or the tubes 44 and 46.

Actuation of the flap valve 51 is effected by means of a vertical rod 60 attached to the eye 50 of crank 49 by means of a bolt 61. The rod 60 at its lower end passes through an inverted U-shaped bracket 63 fixed in any suitable manner to the platform 10. Mounted slidably on the lower end of the rod 60 is a pedal 64, which is held on the rod 60 by means of a nut 65 and a washer 66, the outer end of the pedal 64 being secured rotatably to the platform 10 by means

of a hinge 67 fixed to the platform 10 by screws 68. The lower end of rod 60 is threaded from its lower end to an intermediate point as at 69. Mounted slidably on said threaded portion 69 is a sleeve 70 (see Fig. 6) having an arm 71, which in turn has an upturned end 72, the sleeve 70 being positioned adjustably on the rod 60 by means of nuts 73 received on the threaded portion 69. A coil spring 74 is mounted on the lower end of rod 60 between the sleeve 70 and a washer 75 also received slidably on the rod 60 just above the bracket 63, the spring 74 tending to urge the flap valve 51 into a position closing the exhaust tube 41 and opening the extending tube 44. Mounted on the underside of work support 13 and also on the outer side of tank 15 are pulleys 80, which guide a chain 81. Said chain 81 is attached at its ends to the upturned end 72 of the arm 71 and the outer end of the lever 31.

The blower 20 is driven by means of a motor 90 mounted on an adjustable support 91 on one of the vertical supports 14, the driving connection between the motor 90 and the blower 20 being a belt 92.

In the operation of the apparatus, the operator, by stepping on the pedal 64, opens the stopper 33 of the funnel 22 and also moves the flap valve 51 to a position opening the exhaust tube 41 and closing tubes 44 and 46. Kapok is then delivered through the filling tube 43 into the life jacket or other equipment to be filled. By removing his foot from the pedal 64, the operator causes the stopper 33 to be moved into closed position and also causes the flap valve 51 to close the exhaust tube 41 and open the passage through the extending tube 44 and return tube 46, thereby enabling the excess kapok that remains in the blower 20 to be returned to the tank 15.

Various modifications and changes can be made in the subject device without departing from the scope of the invention.

The invention described herein may be manufactured and used by or for the Government of the United States of America for governmental purposes without the payment of any royalties thereon or therefor.

We claim:

1. A filling apparatus comprising a work support, an enclosed tank adjacent said work support, a blower on said work support, an intake port extending from said blower into said tank, a valve in said intake port, an exhaust port on said blower, a tube connecting said exhaust port with said tank, a valve in said exhaust port arranged to open or close said exhaust port or said tube, and means to operate said valves simultaneously.

2. A filling apparatus comprising a work support, an enclosed tank adjacent said work support, a blower on said work support, an intake tube on said blower extending into said tank, a funnel in said tank on said intake tube, a lever pivoted to said funnel, one end of said lever having a stopper for said funnel, the other end of said lever extending beyond said funnel, an exhaust tube on said blower, said blower being rectangular in cross section, a tube connecting said exhaust tube to said tank, said tube being of rectangular cross section, a flap valve pivoted at the outer meeting point of said connecting tube and exhaust tube whereby said flap valve may close said exhaust tube or said connecting tube, said flap valve being pivoted on a spindle,

and means to rotate said spindle and said lever on said funnel simultaneously.

3. A filling apparatus comprising a work support, a tank adjacent said work support, a blower on said work support, an intake tube leading from said blower into said tank, a funnel on the end of said intake tube, a lever pivoted between its ends on said funnel, a stopper for said funnel one end of said lever, a shelf in said tank below said funnel, a bracket on said shelf, a spring fixed to said bracket and to the other end of said lever, an exhaust tube on said blower, a connecting tube between said tank and an intermediate point of said exhaust tube, a flap valve within said exhaust tube so constructed and arranged as to close either said exhaust tube or said connecting tube, said flap valve being mounted on a spindle, a crank on said spindle outside said exhaust tube, a rod pivoted to said crank, pulleys on said work support, a chain attached to said rod and said other end of said lever and passing over said pulleys, and pedal means to move said rod linearly.

4. A filling apparatus comprising a platform, a work support above said platform, a vertically extending tank adjacent said work support and platform, a blower on said work support, an intake tube on said blower extending into said tank, a funnel on the end of said intake tube, a shelf adjacent and below said funnel, a vertically extending bracket on said shelf, a hinge on said funnel, a lever pivoted between its ends on said hinge, a stopper for said funnel on one end of said lever, a spring fixed to the other end of said lever and to said bracket and urging said stopper into closed position, an exhaust tube on said blower, said exhaust tube being square in cross section, a connecting tube extending between said tank and an intermediate point in said exhaust tube, said connecting tube being of square cross section, a flap valve of rectangular configuration at the intersection of said exhaust tube and connecting tube, said flap valve being mounted on a spindle extending through said exhaust tube, a crank on said spindle outside said exhaust tube, a vertical rod pivoted to said crank, a bracket of inverted U-shape on said platform, a bore in the top of said bracket, said rod passing through said bore, a nut on the lower end of said rod larger in size than said bore, an arm on said rod at an intermediate point thereof, a coil spring on said rod between said arm and said inverted U-shaped bracket, pulleys on the lower side of said work support and on said tank, a chain fixed to said arm and the said other end of said lever and in running engagement with said pulleys, and a foot pedal resting on said platform and attached to said rod.

5. A filling apparatus comprising a support, a blower on said support, an enclosed tank adjacent said support, an intake port on said blower, said intake port being in said tank, an exhaust port on said blower, a passage between said exhaust port and said tank, and valve means to open said intake and exhaust ports and close said passage when said means is in one position, and to close said intake and exhaust ports and open said passage when said means is in another position.

6. A filling apparatus comprising a work support, a tank adjacent said work support, a blower on said work support, an intake tube on said blower extending into said tank, a funnel in said tank on said intake tube, a lever pivoted to said funnel, one end of said lever having a stopper for

said funnel, the other end of said lever extending beyond said funnel, an exhaust tube on said blower, a tube connecting said exhaust tube to said tank, a flap valve pivoted at the outer meeting point of said connecting tube and exhaust tube whereby said flap valve closes said exhaust tube or said connecting tube, said flap valve being pivoted on a spindle, and means to rotate said spindle and said lever on said funnel simultaneously.

7. A filling apparatus comprising an enclosed tank, a blower, an intake tube communicating between said tank and said blower, valve means to close said intake tube when in one position and to open said intake tube when in another position, an exhaust tube on said blower, a connecting tube communicating between said tank and said exhaust tube, valve means to close said exhaust tube when in one position and to close said connecting tube when in another position, and means to operate said valve means simultaneously.

8. A filling apparatus comprising an enclosed tank, a blower, an intake tube communicating between said tank and said blower, valve means to close said intake tube when in one position and to open said intake tube when in another position, an exhaust tube on said blower, a connecting tube communicating between said tank and said exhaust tube, valve means to close said exhaust tube when in one position and to close said connecting tube when in another position, and means to close and to open said intake and exhaust tube valve means simultaneously.

9. A filling apparatus comprising an enclosed tank, a blower, an intake tube communicating between said tank and said blower, valve means to close said intake tube when in one position and to open said intake tube when in another position, means to retain said valve means in normally closed position, an exhaust tube on said blower, a connecting tube communicating between said tank and said exhaust tube, valve means to close said exhaust tube when in one position and to close said connecting tube when in another position, means to retain said valve means in normally closed position, and means to operate said valve means simultaneously.

10. A filling apparatus comprising an enclosed tank, a blower, an intake tube on said blower extending into said tank, a valve means to open and close said intake tube, an exhaust tube on said

blower, a connecting tube extending between said tank and said exhaust tube, a flap valve at the intersection of said exhaust tube and said connecting tube adapted to close said exhaust tube or said connecting tube selectively, and means to operate said flap valve and said intake tube valve means simultaneously.

11. A filling apparatus comprising an enclosed tank, a blower, an intake tube on said blower extending into said tank, valve means to open and close said intake tube, an exhaust tube on said blower, a connecting tube extending between said tank and said exhaust tube, a flap valve at the intersection of said exhaust tube and said connecting tube adapted to close said exhaust tube or said connecting tube selectively, means to retain said valve means in closed position, means to retain said flap valve in position closing said exhaust tube, and means to operate said flap valve and said intake tube valve means simultaneously.

12. A filling apparatus comprising a tank, a blower, an intake tube on said blower extending into said tank, valve means to open and close said intake tube, an exhaust tube on said blower, a connecting tube extending between said tank and said exhaust tube, a flap valve at the intersection of said exhaust tube and said connecting tube adapted to close said exhaust tube or said connecting tube selectively, spring means to retain said valve means in closed position, spring means to retain said flap valve in position closing said exhaust tube, and means to operate said valve means simultaneously.
